(57) CLAIM

The ornamental design for a nightstand as shown and described.

DESCRIPTION

FIG. 1 is a perspective view of the nightstand;
FIG. 2 is a front elevational view of the nightstand;
FIG. 3 is a rear elevational view of the nightstand;
FIG. 4 is a right side elevational view of the nightstand, the left side of which is a mirror image;
FIG. 5 is a top plan view of the nightstand; and,
FIG. 6 is a bottom plan view of the nightstand.
The broken line portions of the drawings are included to show portions of the nightstand that form no part of the claimed design.
